(57) **CLAIM**

The ornamental design for a bench swing, as shown and described.

DESCRIPTION

FIG. 1 is a perspective view of the front and left side of a bench swing.

FIG. 2 is a perspective view of a portion of the left end of the bench swing of FIG. 1, of which the right end is a mirror image.

FIG. 3 is another perspective view of a portion of the left end of the bench swing of FIG. 1, of which the right end is a mirror image.

FIG. 4 is a perspective view of the front of the bench swing of FIG. 1.

FIG. 5 is a perspective view of the front and right side of the bench swing of FIG. 1.

FIG. 6 is a perspective view of the back of the bench swing of FIG. 1; and,

FIG. 7 is a perspective view of the bottom of the bench swing of FIG. 1.

The broken lines in the drawings represent unclaimed environmental subject matter.
